UNITED STATES PATENT OFFICE.

FRIEDRICH WEGMANN, OF ZURICH, SWITZERLAND.

ROLLER-MILL.

SPECIFICATION forming part of Letters Patent No. 276,104, dated April 17, 1883.

Application filed February 10, 1883. (No model.) Patented in England January 15, 1879, No. 180, and June 23, 1879, No. 2,513; in Germany June 19, 1879, No. 9,926, and in Austria September 23, 1879, No. 2,982.

To all whom it may concern:

Be it known that I, FRIEDRICH WEGMANN, of Zurich, in the canton of Zurich, Republic of Switzerland, have invented certain new and 5 useful Improvements in Roller-Mills, of which the following is a specification.

My invention relates to roller-mills for reducing grain and other substances; and the improvements consist in various features and 10 details hereinafter more fully explained, but having reference more particularly to the manner of mounting, adjusting, and driving the rolls, and to an arrangement of the roller-adjusting devices and the feed-controlling mechanism, whereby the feed is stopped simultaneously with the separation of the rolls, whether 15 said rolls continue to rotate or not.

In the accompanying drawings, Figure 1 represents a side elevation of my improved 20 mill, partially in section; Fig. 2, an end elevation, likewise partially in section; Fig. 3, a view illustrating the manner of mounting the adjustable roll; Fig. 4, a sectional view taken on the line $x-x$ of Fig. 3; Fig. 5, a side elevation of the machine, showing its external appearance; Fig. 6, an end view of the same, 25 partly sectioned to illustrate the construction and arrangement of the driving-pulley and its clutch; Figs. 7 and 8, side elevations of the machine, looking from opposite sides, showing the arrangement of belts, when belts are used 30 instead of gearing; Fig. 9, an end elevation, partially in section, of the belted mills shown in Figs. 7 and 8; Figs. 10 and 11, enlarged 35 detail views of the clutch device applied to the driving-pulley; Figs. 12, 13, and 14, views illustrating details of the feed mechanism.

A represents the frame of the mill or machine, which may be of any usual or approved 40 construction affording the requisite rigidity and strength, and B C the grinding-rolls, arranged in pairs, one or more pairs being mounted in each frame. The rolls may be of porcelain, chilled iron, steel, or any other material commonly used for the purpose, and one 45 roll of each pair is made adjustable to and from its companion, which latter is preferably carried in fixed boxes or bearings. By referring to Figs. 3 and 4 the manner of mounting 50 the adjustable roll will be readily understood.

D represents an upright swinging arm, mounted upon a pivot, a , the ends b of which are journaled in frame A, and the arm-sustaining portion of which is set eccentrically with reference to the ends b , so that as the whole 55 is rotated the position of the pivot a is changed, raised, lowered, or moved forward or backward, according to the direction and extent of rotation. One end of the pivot-bolt is threaded to screw into the frame and retain the pivot 60 in place, and a jam-nut, C, is employed, as shown in Fig. 4, to prevent the accidental turning of the pivot after it is properly adjusted.

The long-continued use of the mill is attended with a considerable amount of wear on the parts—the pivots a , as well as others—and in order that there may be no vibration or rattling at that point, in case of wear or failure to produce an accurate fit in the first instance, 70 I provide a threaded stem, d , which passes upward through the lower end of arm D and bears against the pivot a , taking up all play theron. A jam-nut, e , prevents the unscrewing of stem d . Two such arms are used for 75 each adjustable roll, one at each end of the roll, as more plainly seen in Fig. 2, the boxes or bearings f for the ends of the roller shaft or axle being bolted to the arms D, as shown in Fig. 3. The upper ends of arms D are drawn 80 inward, or in the direction of the stationary roll, by means of draw-rods E, one end of which is attached to the upper end of the arm, while the opposite end is attached to a short arm, g , of a lever, F, pivoted to the frame A, or to the 85 hopper-frame, and provided with a sliding or adjustable weight, G, which can be moved along the lever to any desired distance from its pivot h , and thus made to draw roll B toward roll C with whatever force may be necessary. 90

The levers F at both sides of the machine are formed with a second short arm or extension, i , beyond the pivot h , and these arms extend beneath and rest against eccentrics or 95 cams j , formed or secured upon a cross shaft or rod, H, one or both ends of which are furnished with a hand-lever, I, by which the shaft may be turned or rocked. When the rolls are 100 in working position the cams or eccentrics are

raised up, allowing the weights G to depress the levers F, and thereby causing the draw-rods E to draw upon the arms D, and thus hold them up to working position. When, however, it is desired to spread the rolls apart for any purpose—as, for instance, to prevent injury thereto when running empty—the lever I is moved so as to turn down the cams or eccentrics, which then bear upon and depress the short arms i, and consequently elevate the weighted ends of levers F, at the same time, of course, causing the depending arms g to swing back and relieve the rods E of strain from weight G. In order to spread the rolls apart with certainty when the pressure of the weights G is removed, each draw-rod E is furnished with a strong spiral spring, J, arranged as shown in Fig. 1; or, instead of this, the spring may be arranged in any common way for the purpose.

The feed-controlling mechanism of the mill is illustrated in Figs. 1 and 2, and certain details thereof are more fully shown in Figs. 12, 13, and 14.

K represents the feed-hopper, provided with a regulating-gate, k, having a toothed rack, l, on its outer face, in which a pinion, m, carried by a hand piece or lever, n, engages, as shown, so that by raising or lowering the hand-piece the gate will be adjusted as required, a binding or clamping screw, o, being provided to secure the gate at the desired adjustment. At the bottom of the hopper is placed a grooved or corrugated feed-roll, p, and in front of this, and upon the same horizontal plane, substantially, is arranged a second roll, q, having a smooth surface, and traveling quite close to the surface of roll p, a trough or bottom, r, being extended from the rear side of the hopper to the front of roll q, beneath the two rolls, to prevent the grain, middlings, or other material from falling before it reaches the chute or secondary hopper L, by which it is conducted to the rolls B C. The roll p is furnished with a shaft, s, which is carried out beyond the side of the frame A, and is furnished with a loose band-wheel, M, which is prevented by a collar, t, from passing off the end of the shaft.

u represents a hub or boss rigidly secured upon shaft s, and provided with one or more ribs or feathers, v, which project from its outer face along the shaft s, and serve to guide the hub or boss of an internally-toothed gear-wheel, N, which is thus free to slide longitudinally along the shaft, but cannot rotate except with and as the shaft rotates. This gear-wheel has a curved or beveled outer face, and a hub, w, which engages with the hub of wheel M, said hubs being serrated, covered with rubber or leather, or otherwise adapted to lock or bind one upon the other when pressed together with slight force.

x indicates a stiff spiral spring encircling the hub of wheel N, and bearing at one end against the inner face of the wheel, and at the other end against the hub or boss u of shaft s, for the purpose of forcing and holding the

wheel N outward toward wheel M, and to cause and maintain the contact and engagement of the hubs of the two wheels, so that as wheel 70 M is rotated, by belt or otherwise, it is caused to turn wheel N with it, and through said wheel to turn also the shaft s, thereby imparting motion to the feed-roll p. The device or mechanism may be used in this form, or without a second feed-roll, if desired, and with good results. If so used, the hub only of wheel N is required. In practice I prefer, however, to employ the second feed-roll, q, the shaft y of which is provided with a pinion, z, to mesh 80 with the teeth of the internally-toothed wheel N, as shown in Fig. 12. By this arrangement both rolls are caused to turn in the same direction, the roll q at a considerably higher speed than roll p. Roll p, being corrugated, 85 and located directly under hopper K, serves to draw the material therefrom and to carry it to roll q, which raises said material in a thin and regular sheet, and carries it over its top and drops it into hopper or chute L, whence it 90 passes to the rolls B C.

It will be seen that under the above construction and arrangement of parts the spring x will hold the hubs of wheels M N normally in engagement, causing the feed-rolls to turn 95 with the rotation of wheel M. When it is desired to stop the feed without stopping the rolls the wheel N is pressed inward away from wheel M, which latter then runs loosely and freely upon the shaft s, which then remains at 100 rest. Of course if the rolls are stopped the feed necessarily stops, because, as usual, the pulley M is driven by belting from one of the roll-shafts; hence what is required is some means for disconnecting or separating wheels 105 M and N and permitting the former to continue its rotation; but it is important that when this is done the rolls B C be at the same instant spread apart or separated to avoid injury of their faces. To secure these several 110 results simultaneously and conveniently, I provide the shaft H, which carries the eccentrics j, with an arm, O, preferably furnished with an anti-friction sleeve or roller, which arm rides against the curved or beveled outer face of 115 gear-wheel N as the hand-lever I is moved inward to raise the weighted levers F and effect the separation of the rolls, forcing said wheel inward against the pressure of spring x, and holding the wheel in such position so long as 120 the hand-lever I remains in its said position. The wheel N and feed-rolls consequently cease to rotate and remain at rest until the hand-lever I is again thrown outward, permitting the weighted levers F to restore the roll B to 125 its working position, the outward movement of said lever also carrying outward the arm O and permitting the spring x to again cause the engagement of the hubs of wheels M and N, and the consequent starting or recommencement of the feed.

I would here remark that the details are not essential, though I have shown and described what I deem the most convenient and satis-

factory arrangement; but I believe myself to be the first to provide for simultaneously stopping the feed and spreading the rolls, and therefore, while claiming the mechanism here shown and explained, and believing it to be admirably adapted to carry out my invention in this particular, I do not limit myself to the specific mechanism shown.

The mill is designed to be driven by gearing or belting, as may be preferred, the arrangement of each being clearly illustrated in the several figures of the drawings, it being understood that the gearing may be at one or both ends of the rolls.

15 I will now refer to Figs. 1, 2, 3, 4, 5, and 6 for the purpose of explaining the arrangement of the gearing, which is particularly designed to overcome the present or usual difficulty of providing gear suitable to be used with rolls 20 varying slightly in diameter, as commonly happens with all kinds of rolls, but more especially with those made of porcelain.

In order to entirely remove an imperfection or flaw, it is often necessary to turn the roll 25 down smaller than the standard size; or the rolls wear away in use, and then the gearing gives but indifferent results if arranged in the ordinary way. To obviate these difficulties, and to compensate for wear of the pinions, 30 rolls, shafts, &c., I provide the shafts of rolls B C each with a pinion wholly independent of that of the companion roll; and I further provide a counter-shaft, P, carrying at one end a band wheel or pulley, Q, and at the other end 35 a gear-wheel, R, which gears with and drives pinion T of roll C, and likewise gives motion to pinion U of roll B through the medium of an adjustable intermediate gear or pinion, V.

It will thus be seen that as roll B swings or 40 moves away from roll C its gear U moves circumferentially about the gear V, and although the pivotal point of the swinging arms D is not concentric with gear V the line of movement corresponds so nearly to the circumference 45 of said gear that the slight movement due to the separation of the rolls does not perceptibly change or affect the mesh of the pinions U V. The pinion V is carried by a journal or axle, W, which is guided up and down in a slot, X, in the frame A, being raised and lowered by a nut, Y, screwed upon a rod, Z, jointed to the axle or journal W, said nut working between lugs or ears a', cast upon frame A, and through which the rod is carried, as shown in 50 Figs. 1, 3, 4, 5, and 6, the slot X being curved on the arc of a circle concentric with counter-shaft P, so that in adjusting the pinion V it is kept always at the same distance from the counter-shaft. This adjustment permits gears 55 of different sizes to be substituted for gear U.

When two sets of rolls are employed it is advantageous to use driving-belts instead of gearing, though it is apparent that the gearing may be applied to any desired number of 60 sets of rolls in the same mill or machine.

The arrangement of the belts is illustrated

in Figs. 7 and 8, and requires four belt-wheels at each side or end of the mill.

The counter-shaft P is employed, the same as where gearing is used, and from a pulley, 70 A', at one end of the counter-shaft a belt, D', is carried around pulleys E' F' on the shafts of rolls B B', and also about a band or belt tightener pulley, G', arranged below and between the pulleys E' F'. At the opposite side 75 or end of the machine the rolls C C' are furnished with belt-pulleys H' I', and the counter-shaft P is provided with a similar pulley, J', and a belt-tightening pulley, K', is arranged below pulley J', all as shown in Fig. 7. As 80 also seen in said Fig. 7, the belt L' passes from counter-shaft pulley J', between and around pulleys H' I', and thence to and around tightener-pulley K', while belt D' passes from counter-shaft pulley A', around the outer sides 85 of pulleys E' F', and down between them to tightener-pulley G', by which arrangement the rolls B B' are driven in one direction and the rolls C C' in the reverse direction.

The tightener-pulleys G' and K' are each 90 carried by a slide, O', moving in suitable guides on frame A, and are caused to act with a constant elastic pressure by reason of springs M', the compression or force of which is regulated and controlled by set-screws N'. 95

The band-wheel Q, through which motion is imparted to the counter-shaft P, is loose upon said counter-shaft, but is made with a beveled flange or rim, f', which is turned to fit snugly within the rim of wheel A' when the two are 100 forced together. The wheel A' is free to move longitudinally upon shaft P, but is prevented by a spline or feather, h', (shown in Fig. 10.) from rotating thereon, and its hub is circumferentially grooved to receive a stud or roller, 105 g', projecting from a hand-lever P', by which lever the wheel may be moved along the shaft to cause it to clutch with or disengage from wheel Q. This construction and arrangement will be more readily understood by referring 110 to Fig. 10, where it will also be seen that the hub of the wheel Q is grooved, and encircled by a band or collar, k', which is connected by links l' m' to the hub or boss n' of wheel A' to prevent the accidental or undue separation 115 of the wheels. In Fig. 6 the wheel Q is represented as fitting over the wheel A'; or, in other words, the arrangement shown in Fig. 12 is simply reversed.

The hand-lever P' may be held at any desired 120 adjustment by a locking-dog, o', engaging in a rack, p', or by any similar and common locking device.

The employment of a friction-clutch permits the machine to be stopped readily and 125 started gradually without disarranging the belts or varying their tension, and is of great importance in this particular class of machines.

When the toothed gearing is used it is found that the gear-wheels exert a force upon the 130 journals of the rolls, tending to force said rollers together at the geared ends, and to coun-

teract this tendency I provide a yielding or elastic pressure-rod, Q' , passing through ears or guides on the frame A , and bearing at one end against the swinging arm D at a point above its pivot. The rod is encircled by a strong spring, R' , one end of which bears against a shoulder or head, i' , at or near the outer end of the rod, while the other end bears against the stationary lug or ear j' , through which the rod passes, as more plainly shown in Fig. 5.

S' is a nut screwed upon the rod in rear of lug j' , and which, being screwed backward or forward, controls the distance to which the rod may project, and consequently the distance to which the arm D may move inward before coming in contact with the rod and encountering the resistance of the spring.

It is found in practice that the material acted upon is liable to cake upon the rolls, and that a single doctor-plate or scraper fails to perfectly clean a roll at all times; hence I provide two, three, or more scrapers for each roll.

When the mill is first started, and before the parts have all acquired a perfect working adjustment relatively to each other, the scrapers will be found to touch some portions of the rolls and to clear other portions, and in order to cause them to quickly wear to fit perfectly the faces of the rolls I provide the levers which carry them with adjustable weights, which are set well out from the pivots until the plates are worn to conform perfectly to the surfaces of the rolls, after which they are set in nearer to the pivots to avoid unnecessary wear of the rolls or plates.

The arms g of levers F are provided with two or more notches to permit the rods E to be connected thereto nearer to or farther from the pivots h , and a nut is applied to each end of said rod to permit the proper adjustment of parts to secure the desired position of lever F .

The mill constructed as thus described is compact, efficient, and convenient. By the arrangement of belting shown and described the mill is rendered complete in itself, and does not require a specially-located counter-shaft for driving it. The main driving-belt, being carried to wheel Q in any direction from a driving-wheel in the same vertical plane, will drive the mill, whereas with other arrangements of belts it has been necessary to have the driving-wheel located in a certain position.

A second tightener-wheel, T' , may be employed on the driving side of the mill, if found desirable, to give proper friction of the belt.

A guard is placed over the gearing, as shown in Figs. 2 and 4.

Although I have for the purpose of fully disclosing my invention explained its application to varying styles of machines, I do not herein claim the construction or arrangement of the toothed gearing, the friction-clutch, or the pressure-rod, which features I reserve

as part of the subject-matter of another application.

Having thus described my invention, what I claim is—

1. The combination, in a roller-mill, of rolls $B C$, swinging arms D , carrying roll B , levers F , formed with arms g , weights G , applied to said levers, and rods E , extending from the arms g to the swinging arms D , and connected therewith, whereby the weighted levers are caused to draw the roll B toward the roll C . 70

2. In combination with rolls $B C$, movable supports D , carrying roll B , weighted levers F , having arms g , rods E , connecting the movable supports D and arms g , and a shaft provided with eccentrics, adapted and arranged to raise the weighted levers, substantially as set forth. 80

3. In combination with a swinging roller-support, and with an adjustable pivot therefor, a take-up, substantially such as shown, to compensate for the wear of the pivot or its seat. 85

4. The combination of swinging arm D , pivot a , and take-up d , all constructed and arranged substantially as shown and described. 90

5. In a roller-mill, the combination of a roller mounted in stationary bearings, a roller mounted in movable bearings, a feed-regulating device, and mechanism adapted and arranged to simultaneously stop the feed and separate the rolls. 95

6. In combination with a fixed roll and an adjustable roll, a feed-regulating mechanism, a roll-spreading mechanism, and a lever or hand-piece, common to both the spreading mechanism and the feed-regulating mechanism, whereby the stopping and starting of the feed may be effected simultaneously with the spreading apart or drawing together of the grinding-rolls, and by a single operation. 100

7. In a roller-mill, the combination of feed-roll shaft s , band-pulley M , arranged to turn loosely upon said shaft, sliding wheel N , and cross-shaft H , provided with arm O , adapted to separate the hubs of band-wheel M and wheel N , as and for the purpose set forth. 110

8. In a roller-mill, the combination of feed-rolls $p q$, one provided with pinion z and the other with internally-toothed gear-wheel N and loose band-wheel M , the gear-wheel being pressed toward the band-wheel by a spring, x , and prevented from turning on its shaft, and the cross-shaft H , provided with arm O , as 115 and for the purpose explained. 120

9. In a roller-mill, the combination of rolls $B C$, movable and fixed supports for said rolls, respectively, weighted levers F , connected with said movable supports, substantially as shown, shaft s , band-pulley M , loosely mounted upon said shaft, wheel N , free to slide but held against rotation upon shaft s , the feed-roll, and cross-shaft H , provided with hand-lever I , eccentrics j , and arm O . 125

10. The herein-described roller-mill, consisting of frame A , rolls $B B' C C'$, each provided 130

with a band-pulley, counter-shaft P, provided with a band-pulley at each end, and with a driving-wheel, Q, and the tightener-pulleys G' K', all substantially as shown and described.

5 11. In a roller-mill, the combination of two sets of rolls, the rolls of each pair arranged to rotate toward each other, a counter-shaft arranged in the frame of the mill, and provided with a band-pulley, whereby it may receive
10 motion from a prime motor, and two endless belts passing from pulleys on the counter-shaft

to and around pulleys on the roller-axles in the manner shown and described, and neither passing outside of the machine, whereby the mill is rendered complete in itself, and ready 15 for operation upon the application of power to the driving-wheel of the counter-shaft.

FRIEDRICH WEGMANN.

In presence of—

FRIEDRICH SCHABELITZ,
ROBERT STOLZ.
